UNITED STATES PATENT OFFICE.

CHARLES FREMONT HENRY, OF BOW ISLAND, ALBERTA, CANADA.

ENGINE-VALVE.

1,187,834.

Specification of Letters Patent. Patented June 20, 1916.

Application filed March 9, 1914. Serial No. 823,419.

To all whom it may concern:

Be it known that I, CHARLES FREMONT HENRY, of the town of Bow Island, in the Province of Alberta, Canada, have invented 5 certain new and useful Improvements in Engine-Valves, of which the following is the specification.

The invention relates to a valve applicable to steam and other such engines and 10 the object of the invention is to do away with the various slide and rocker valves, valve gears and eccentrics now in common use on engines and substitute therefor a revolving valve of the barrel type whose motion is continuous, thus causing no jerks or 15 jars, and supplying one which may be run at a very high rate of speed without danger of displacement of the valve or injury to it.

A further object of the invention is to 20 provide a steam tight valve which may be readily operated to reverse the engine when required such valve being constructed so that it can be easily set without removal and can also be quickly removed when required 25 for repair purposes.

It consists essentially in the arrangement and construction of parts hereinafter more particularly described and later pointed out in the appended claims.

30 Figure 1 represents a side view of an engine with the valve applied. Fig. 2 is a plan view of the same. Fig. 3 represents an enlarged detailed horizontal sectional view through the valve and engine cylinder. Fig. 35 4 is a vertical sectional view through the valve and cylinder, the section being taken in the plane denoted by the line X—X' Fig. 3. Fig. 5 is a perspective view of the controlling sleeve. Fig. 6 is a vertical section 40 view through the valve, the section being taken in the plane denoted by the line Y—Y' Fig. 3. Fig. 7 is a vertical sectional view through the valve and ports showing the initial setting of the sleeve required to 45 produce a forward rotation of the engine. Fig. 8 is a vertical sectional view through the valve and ports showing the initial setting of the sleeve required to produce a reverse rotation of the engine.

50 In the drawings like characters of reference indicate corresponding parts in each figure.

I might explain that the present invention is in reality an improvement on the valve 55 as set forth in United States Patent No.

1055531 which patent was issued to another party and myself as co-inventors on the 11th day of March 1913. In the said patent a disk valve is shown, the passage of the steam through the valve being controlled by 60 a reversing disk having suitable ports therein and controlling the passage of the steam from the valve ports to the engine ports. In the present application the valve takes the form of a rotary barrel having suitable 65 ports therein which is inclosed within a sleeve, the sleeve controlling the passage of the steam from the interior of the valve to the engine ports.

Referring now to the drawing, 1 represents a suitable base plate supporting an engine cylinder 2 and a set of bearing blocks 3 and 4 in turn carrying a cross shaft 5. The shaft is supplied with a wheel 6 and a bevel gear 7, the wheel being supplied with 70 an eccentric pin 8.

9 is a rod connecting the pin 8 with a piston rod 10 secured to a piston 11 which operates in the cylinder.

Adjoining the side of the cylinder I have 80 formed a cylindrical valve chamber 12 which is preferably cast integral with the cylinder and is fitted with two removable end plates 13 and 14.

15 and 16 are ports leading from the wall 85 of the chamber to the head and crank ends of the cylinder respectively.

17 is a hollow rotary valve in the form of a cylinder or barrel and contained within the chamber 12, one end of the valve being 90 provided with an extending feed pipe 18 mounted in a suitable bushing carried by the end plate 14 while the other end of the valve is supplied with an extending shaft 19 rotatably mounted in a suitable bushing presented by the end plate 13.

The horizontal axes of the shaft and the inlet pipe are alined and they are mounted in the end plates so that the said valve is arranged concentric to the chamber.

100 20 is a controlling sleeve surrounding the body of the valve and presenting a pair of entrance ports 21 and 22 designed to register, depending on the position of the said sleeve, with the ports 15 and 16. I prefer 105 that this sleeve be made from spring steel so that it can be slipped on the valve and will maintain a tight fit.

23 and 24 are inlet ports passing through the walls of the valve and arranged at 180° 110

apart and designed in the rotation of the valve to register with the ports 21 and 22 respectively.

25 and 26 are exhaust ports in the form of 5 slots located in the face of the valve and arranged at 180° apart and designed to register also with the ports 21 and 22 respectively in the rotation of the valve.

It is to be noticed that the body of the 10 valve is somewhat shorter than the length of the chamber 12 so that exhaust chambers 27 and 28 are provided at each end of the valve which chambers are continuously in communication with the exhaust slots 25 and 26 15 respectively.

In order that the sleeve can be adjusted to open or close the ports I have made it somewhat longer than the valve so that one end overhangs the valve. This end is fitted with 20 a rack 29 which is engaged by a pinion 30 fixed on the inner end of a spindle 31 mounted in the plate 13. The spindle is provided with a controlling lever 32.

The extending end of the shaft 19 is 25 mounted in suitable brackets 33 and carries a bevel wheel 34 which meshes continuously with the bevel gear 7 already referred to.

The gear and pinion are constructed so 30 that the shaft 19 rotates at the same speed as the crank shaft. In other words by this arrangement the valve is compelled to rotate one half a revolution for each stroke of the piston.

The wheel 34 is supplied with an extending 35 sleeve carrying a set screw 34' which allows the adjustment of the wheel on the shaft.

The inlet pipe 18 communicates with a stationary supply pipe 35, the connection between 40 the supply and feed pipes being such that a steam tight joint is formed while allowing of the rotation of the feed pipe in the supply pipe.

In setting up the valve it is preferable to 45 first turn the engine to what is commonly called "dead center" position and then afterward adjust the valve by undoing the set screw 34' until the ports in the valve are directly opposite the ports 15 and 16.

50 The operation of the engine is now described: Live steam enters the valve from the pipe 35 through the pipe 18 and is admitted in the rotation of the valve alternately to the head and crank ends of the cylinder through the ports 23, 21 and 15 and the ports 24, 22 and 16. As the live steam is entering one end of the cylinder the exhaust steam is being freed from the opposite end of the cylinder. The exhaust steam passes 55 through the ports 15, 21 and 25 and 16, 22 and 26 and finally passes from the exhaust chambers 27 and 28 to the exhaust pipes 36. The amount of steam fed to the cylinder 60 can be controlled by manipulating the lever

32 which when turned causes the sleeve to 65 rotate so as to open or close the ports 21 and 22 as the case may be.

Particular attention is now directed to Figs. 7 and 8 of the drawings wherein particular settings of the valve sleeve are shown. 70

Assuming that the sleeve has been previously turned to closed position that is with its ports turned away from the ports 15 and 16 and assuming also that the engine shaft is turned or cranked to bring the engine to 75 "dead center" position which position effects the registration so to speak of the valve ports with the cylinder entrance ports and that it is required to start the engine in the forward direction. To accomplish this 80 the sleeve is turned by means of the lever to the position shown in Fig. 7 of the drawings in which position it admits a small quantity of live steam to the cylinder. The admission of this steam to the cylinder would cause the piston to move and consequently 85 rotate the valve. Owing to the setting of the sleeve, as shown in the said latter figure the engine if it starts in the reverse direction continues to rotate in that direction for the 90 reason that the entry port of the valve will immediately sweep past the opening in the sleeve and cut off the steam. However if the engine turned in the forward direction steam would be admitted to the cylinder for the 95 complete sweep of the valve inlet port past the sleeve opening. Sufficient steam would in this way be admitted before the valve closed to start the engine.

If it is required that the engine operate 100 in a reverse direction the sleeve is turned to the position shown in Fig. 8 of the drawings. In this position it will be seen that only a small amount of steam can enter the cylinder before the valve closes if the engine rotates in the forward direction, not enough to start the engine. However if the engine turns or starts in the reverse direction steam will be admitted to the cylinder during the complete period that the valve 110 port sweeps across the sleeve opening; there would accordingly be sufficient steam to start the engine.

In both cases once the engine has started the sleeve will be turned to completely open 115 the ports and admit the full steam supply.

What I claim as my invention is:

1. The combination with an engine cylinder, of a cylindrical valve casing adjoining the cylinder and communicating through 120 suitable ports with the head and crank ends of the engine cylinder, end plates closing the ends of the chamber, a sleeve rotatably mounted in the casing and having suitable ports passing through the wall thereof and 125 designed to register with the aforesaid ports, means for adjusting the position of the sleeve and casing, a hollow rotary cylin-

drical valve mounted within the sleeve, said valve having the ends thereof closed and set back from the end plates of the chamber and providing exhaust chambers and being fitted further with inlet ports passing through the walls thereof and exhaust ports in the form of slots located in the outer face thereof and opening to the exhaust chambers, said ports being arranged to register 10 in the rotation of the valve with the ports of the sleeve and means for admitting live steam to the interior of the valve, as and for the purpose specified.

2. The combination with an engine cylinder, of a cylindrical valve casing adjoining the cylinder and communicating through suitable inlet and exhaust ports with the head and crank ends of the cylinder, end plates closing the ends of the valve 15 chamber, a sleeve rotatably mounted in the chamber and fitted with ports designed to register with the latter ports, means for adjusting the position of the sleeve, a hollow cylindrical valve rotatably mounted in the 20 sleeve and having the ends thereof set in from the end plates and thereby providing exhaust chambers and supplied further with a pair of inlet ports opening through the wall of the valve and communicating with the interior thereof and a pair of exhaust ports in the nature 25 of slots formed in the wall thereof and communicating continuously with the exhaust chambers, said ports being designed in the rotation of the valve 30 to register with the sleeve ports, a spindle secured to one end of the valve, said spindle passing through one of the end plates means for rotating the spindle to rotate the valve, a feed pipe extending from the other end 35 of the valve and rotatably mounted in the other of the end plates and a stationary supply pipe communicating continuously 40 with the feed pipe, as and for the purpose specified.

3. The combination with an engine cylinder, of a cylindrical valve casing adjoining the cylinder and communicating through suitable inlet and exhaust ports with the head and crank ends of the cylinder, end plates closing the ends of the valve chamber, a sleeve rotatably mounted in the chamber and fitting with ports designed to register with the latter ports and supplied further and at one end with a rack, a pinion 45 engaging with the rack and carried by a spindle rotatably mounted in the adjoining end plate, a controlling lever carried by the spindle, a hollow cylindrical valve rotatably mounted in the sleeve and having the ends thereof set in from the end plates 50 and thereby providing exhaust chambers and supplied further with a pair of inlet ports opening through the wall of the valve and communicating with the interior thereof and a pair of exhaust ports in the nature 55 of slots formed in the wall thereof and communicating continuously with the exhaust chambers, said ports being designed in the rotation of the valve to register with the sleeve ports, a spindle secured to one end 60 of the valve, said spindle passing through one of the end plates, means for rotating the spindle to rotate the valve, a feed pipe extending from the other end of the valve and rotatably mounted in the other of the end 65 plates and a stationary supply pipe communicating continuously with the feed pipe, as and for the purpose specified.

Signed at Winnipeg this 2nd day of January, 1914.

CHARLES FREMONT HENRY.
